SELF-LUBRICATING PUMP

Henry J. Rand, Bratenahl, Ohio, assignor to H. J. Rand Washing Machine Corp., Bratenahl, Ohio, a corporation of Delaware

Application January 31, 1948, Serial No. 5,624

5 Claims. (Cl. 103—117)

1

The present invention is related to improvements in means for supplying lubrication automatically to a rotary pump of the type having rotating flexible vanes.

An object of the present invention is to supply a reservoir of liquid on the outlet side of a pump of the type described together with a conduit for leading a limited amount of the collected liquid back to the rotating impeller of the pump so as to lubricate the same.

Another object of the present invention is to provide means for insuring that the liquid fed back to the pump for lubricating purposes will not contain lint or the like.

Still another object of the present invention is to provide means for feeding a lubricating liquid from a reservoir to the rotary vane pump at a point near the inlet where the suction is sufficient to provide a flow of liquid into the pump but where the suction is insufficient to suck the reservoir dry.

Other objects and advantages of the present invention will be apparent from the accompanying drawings and description and the essential features will be set forth in the appended claims.

In the drawings,

Fig. 1 is a side elevational view partly broken away and illustrating one embodiment of my invention;

Fig. 2 is a view partly in section and partly in perspective showing another modification of my invention; while

Fig. 3 is a view similar to Fig. 1 showing still another modification of my invention.

My invention is applicable to almost any pump having rotating vanes of rubber-like material but I have chosen to illustrate apparatus which is particularly adapted for use with a washing machine of the general type shown in my co-pending application Serial No. 682,322, filed July 9, 1946, now Patent No. 2,472,682. In such a combination the pump 10 is connected by the line 11 with the interior of a flexible bag within which the laundry is washed. At the close of a washing operation, the pump 10 is started up and pumps the dirty wash water through the inlet 11, past the outlet 12 through a reservoir 13 to a final discharge conduit 14. Experience has shown that where the vanes of the pump are of rubber-like material, it is disadvantageous to have the pump run dry. Among the disadvantages are the excessive friction and wear on the impeller, the high starting and running torque and the excessive noise caused by the pump running dry.

To overcome the above-mentioned disadvantages, I have provided the reservoir 13 on the outlet side of the pump 10 having a portion of the reservoir at 13a below the outlet 12 so that even when the pump has been shut down there will be

2

liquid remaining in the reservoir portion 13a. A conduit 15 connects the reservoir 13 with the inlet side of the pump 10 so that liquid is always available flowing back to the pump to lubricate the same. When the pump has remained idle for a considerable period of time, it is nevertheless lubricated immediately upon starting up. Where the pump is drawing liquid and air from a flexible bag as mentioned in my copending application, it will not pump a good vacuum if it runs dry and furthermore, the friction and wear are excessive if the pump does run dry. During such a period of pumping a partial vacuum, the line 15 supplies lubrication to the vanes of the pump.

In the modification of Fig. 2 I have shown a similar installation including the pump 10 with its inlet 11 and its outlet 12. In this case the reservoir 16 is of elongated type and the discharge into the reservoir is at one end of the elongated chamber while the final outlet conduit from the reservoir 17 is located at the far end thereof. This type of reservoir also supplies a greater volume of liquid for pump lubricating purposes. Preferably also, I provide in the reservoir 16 means for insuring that lint and other loose materials will not be carried back through the conduit 18 for the lubrication of the pump. In the present instance, this means comprises a foraminous plate 19 which forms a partition between the upper and lower parts of the reservoir 16.

In the device of Fig. 2 I have shown diagrammatically the best location for the connection 20 where the line 18 leads into the housing of the pump 10. Here it will be noted that the inlet 11 and the outlet 12 are centered upon a common line A. This line is at right angles to the axis of the rotor 21 which is coaxial with the cylindrical housing of the pump. The vanes 22 are adapted to contact the cylindrical housing through a major portion of their travel but a cam 23 is provided between the inlet and outlet which causes the vanes to bend toward the pump outlet as the vanes rotate in the direction of the arrow of Fig. 2. This action of the vanes causes a partial vacuum in the chamber 24 adjacent the inlet 11 and causes a pressure in the chamber 25 adjacent the outlet 12. This provides the pumping action. The location of the inlet 20 where the conduit 18 connects with the housing of the pump is in the zone traversed by the rotating vanes and positioned near enough the inlet 11 to have a slight vacuum but not such a great vacuum as to suck the reservoir 16 dry. I find that a suitable position for the opening 20 is in general between the line B which is 30 degrees below the line A and the line C which is 45 degrees below the line A. It will be noted that these lines run from the intersection of the line A with a vertical plane D extending dia-

metrically through the axis of the pump impeller.

In the modification of Fig. 3 I have shown an improvement over the device of Fig. 1 which is adapted to remove lint from the liquid passing backward through the line 15 to lubricate the pump. All of the parts in Fig. 3 are like those of Fig. 1 except that which is about to be described. Here a foraminous partition 26 divides the reservoir 13' into upper and lower chambers 27 and 28 respectively. It will be noted that this partition slopes upwardly and outwardly from a point just below the pump discharge or outlet 12. It results from this arrangement that lint and other extraneous material is filtered out of the discharge from the pump before it can pass to the lower portion of the reservoir 28 where it is available to flow through the line 15 for pump lubricating purposes. By sloping the partition 26 in the manner indicated, the discharge fluid coming out of the pump discharge 12 sweeps upwardly and outwardly along the plate 26 so that it is self-cleaning and all particles caught on the plate are eventually washed out the discharge pipe 14.

What I claim is:

1. In combination with a liquid and air pump having a generally cylindrical housing with an inlet and an outlet and a cam between said inlet and outlet, a rotor mounted for rotation about an axis coaxial with said cylindrical housing, said inlet and said outlet being centered on a common line at right angles to said axis and adjacent one side of said housing, said rotor having radially extending flexible and resilient vanes extending into engagement with said housing and bent against said cam and toward said outlet by rotor rotation, a liquid reservoir communicating with and below said outlet, and a conduit communicating between said reservoir and that portion of the interior of said housing opposite said cam separated from said inlet by at least one vane and nearer to said inlet than said outlet whereby, when said rotor is pumping air, liquid caught in said reservoir is sucked back through said conduit slowly to lubricate said rotor.

2. In a pump having a generally cylindrical housing with a rotor mounted for rotation about an axis coaxial with said housing and wherein said housing is provided with an inlet and an outlet centered on a common line at right angles to said axis near one side of said housing, a cam extending into said housing between said inlet and outlet, said rotor having radially extending flexible and resilient vanes extending into engagement with said housing and bent against said cam and toward said outlet by rotor rotation, a liquid reservoir communicating with said outlet, and a conduit communicating between said reservoir and that portion of the interior of said housing opposite said cam traversed by said vanes and lying approximately thirty to forty-five degrees below said common line as measured from the intersection of said common line with a plane extending vertically through said axis, said conduit being positioned nearer to said inlet than said outlet.

3. In a pump having a generally cylindrical housing with a rotor mounted for rotation about an axis coaxial with said housing and wherein said housing is provided with an inlet and an outlet centered on a common line at right angles to said axis near one side of said housing, a cam extending into said housing between said inlet

and outlet, said rotor having radially extending flexible and resilient vanes adapted to bend against said cam and toward said outlet when contacting said cam, said vanes being substantially at right angles to said axis during the major portion of travel about said axis, a liquid reservoir extending below said common line, a conduit connected at one end to the bottom of said reservoir and at the other end to the interior of said housing at a point between said inlet and said outlet opposite said cam and nearer to said inlet than said outlet where said vanes are substantially at right angles to the axis of said rotor, whereby lubricating fluid is delivered in small proportions to said rotor.

4. In a pump, a rotor having flexible vanes, a housing with an inlet and an outlet centered on a common line at right angles to the axis of said rotor and adjacent one side of said housing, a cam between said inlet and said outlet, a liquid reservoir having a communicating connection with said outlet, a foraminous partition in said reservoir below said connection and extending upwardly away from said connection, there being a liquid outlet from said reservoir above said partition, and a conduit interconnecting said reservoir at a point below said partition and the interior of said housing at a point between said inlet and said outlet but nearer to and below said inlet and separated therefrom by at least one of said vanes.

5. In a pump, a rotor having flexible vanes, a housing with an inlet and an outlet centered on a common line at right angles to the axis of said rotor and adjacent one side of said housing, a cam between said inlet and said outlet, a liquid reservoir having a communicating connection with said outlet, said reservoir being elongated in a direction extending away from said connection, a foraminous partition in said reservoir below said connection and extending upwardly away from said connection, there being a liquid outlet from said reservoir above said partition, and a conduit interconnecting said reservoir at a point below said partition and the interior of said housing at a point below said inlet and separated therefrom by at least one of said vanes.

HENRY J. RAND.
